UNITED STATES PATENT OFFICE.

HENRY WARNER AND BENJAMIN F. PALMER, OF BOSTON, MASSACHUSETTS.

IMPROVEMENT IN VENTILATING-WINDOWS FOR TENTS.

Specification forming part of Letters Patent No. 35,963, dated July 22, 1862.

To all whom it may concern:

Be it known that we, HENRY WARNER and BENJAMIN F. PALMER, both of the city of Boston, in the county of Suffolk and Commonwealth of Massachusetts, have invented a new and useful Improvement in Tents; and we do hereby declare that the following specification, taken in connection with the drawings making a part of the same, is a full, clear, and exact description thereof.

Figure 1 is a perspective view of the tent, showing one of the ventilators open and the cowl raised. Fig. 2 shows the flap closed which forms the door. Figs. 3 and 5 are views of two varieties of tent-poles, either of which may be used with our tent. Fig. 4 exhibits the appearance of the apex of the tent when the cowl is down.

The variety of tents now in most common use in the United States Army is the one invented by H. H. Sibley, and known generally by his name. This tent is provided with a cowl or a secondary covering for the apex; but it is distinct from the tent itself, and is capable of being adjusted so as to effect ventilation only from the outside, thus involving the necessity of considerable trouble to accommodate the opening at the peak to any change in the direction of the wind.

The first part of our invention consists in an arrangement for ventilating the tent by the use of a cowl or hood, which is permanently attached to the tent, and which can be readily operated by any person from the inside in such a manner as to cause the top of the tent to be open toward all points of the compass, or open only toward such points as are desired.

A, Fig. 1, represents a conical tent of the usual size, its base being eighteen feet in diameter and its height thirteen feet. It is secured to the ground by loops *n* and tent-pins *m*, in the usual way, and is provided with the well-known flap extending around the base, upon which sods of earth can be heaped to exclude a draft of air at the bottom. The tent is sustained, when pitched, by a single central pole, Figs. 3 or 5, presently to be described. The upper extremity of the pole terminates with an iron point of two or three inches in length provided with a shoulder. The iron point is inserted through an eyelet in the apex, the shoulder *h*, Fig. 5, sustaining the canvas.

Near the apex of the tent are cut a number

of openings similar to *d*, Fig. 1. We think that three openings, with long diameters of eighteen inches and short diameters of six inches, are amply sufficient for all purposes of ventilation; but the size as well as the number can be increased, if desired. A hood, *C*, securely sewed to the tent near the apex, extends down below the openings *h* and effectually closes them, as shown in Fig. 4. The cords *g g g*, hanging by the side of the tent-pole at a convenient height to be seized by the hand, pass through eyelet-holes *e e e*, Fig. 5, near the apex in the canvas of the tent proper, and are led through rings or eyes attached to the under side of the cowl to a point below the edge of the cowl, passing through eyes *b b* on the outside of the tent a convenient length—say two or three feet—at which points weights *a a a* are attached to them. Each cord is securely fastened to the edge of the cowl, so that as the cord is pulled from the inside of the tent the edge of the cowl will be raised above one of the openings. If all the cords are pulled, the cowl will be gathered about the apex in the form shown in Fig. 1, forming a sort of wind-sail or awning over each opening, while a free passage for the exit of air or smoke is allowed. As each cord is relaxed the weights *a a a*, attached to the other end, draw back the cowl over the openings which have been uncovered. It is evident that by this arrangement the tent can be ventilated in any direction with the greatest facility, or the opening changed from one side to the other without any more trouble than is involved in operating the cords *g g g*.

The second part of our invention consists in an improved window, *I*, Fig. 1, so arranged that the size of the aperture can be regulated at pleasure from the inside of the tent, and which, when closed, shall effectually exclude both storms and wind. The elliptical openings *I*, opposite to each other, are cut in the wall of the tent, each of about double the area of one of the openings *d* near the apex, though the size as well as the number of the openings for windows may be varied. About four inches from the end of the short diameter on each side, and parallel to the long diameter, two flaps, *s s*, are sewed, the outer edge of each of which is welded over a cord. Across the top of the window, at right angles to each of the side flaps and about four inches from

the end of the long diameter, a flap, J, is sewed to the wall of the tent on all sides, except the lower one. The shutter D, of sufficient size to cover the window, is provided with a number of clasps, t t t, which span the welted edges of the side flaps and enable the shutter to be slid up and down over the aperture. A cord, q, attached to the upper extremity, and another cord, r, attached to the lower extremity of the shutter, pass through eyelets in the canvas of the tent, as shown, so that by pulling the cord q from the inside the shutter is drawn up underneath the flap J and the aperture completely closed. By operating the cord r the shutter can be opened.

The third part of our invention consists of an improved tent-pole capable of being adjusted to different lengths to accommodate the variations in the length of the canvas. It consists of two parts, E and G, Fig. 5, the first part of tough wood and the second part of metal. The upper part, E, is provided with a metallic shank, H, in which are a series of holes at small distances apart. This shank is fitted to slide freely in the cylindrical part G, which is also provided with a series of holes corresponding to the holes in the shank. Upon the upper end of the socket G, placed so as not to interfere with the movement of the shank H, is a fulcrum-arm, U. A rod of steel, which at other times can serve as a crane upon which to hang a kettle, is now inserted in one of the holes in the shank H, and being used as a lever with U as a fulcrum the canvas can be strained to any tension desired. A pin, attached by the chain J to the socket G, is now inserted into

any hole under the shank H which happens to coincide with one of the holes in the socket, and the length of the pole is determined.

Instead of constructing the pole so that one part of it shall slide inside the other part, we contemplate sliding the two parts upon a scarf-joint, as shown in Fig. 3. The end of a rope or strong cord is passed through a hole near the lower end of one of the parts and knotted on the outside. The rope is then received through a hole or block near the extremity of the other part, a groove being cut in the faces which are in contact to accommodate the rope. Two bands of iron, P P, embrace both parts, the bands being made fast to the part F only. It is apparent that by this arrangement the same effect will be produced as by the one above described.

What we claim as our invention, and desire to secure by Letters Patent, is—

1. A secondary hood or cowl attached to the canvas of the tent near the apex, where the same is so arranged that it can be raised at one or more points by cords worked from the interior of the tent and returned to position by weights or their equivalents, the whole operating in the manner substantially as described.

2. A sliding canvas shutter, D, arranged substantially as described, in combination with an aperture, I, for the purposes specified.

HENRY WARNER.
B. F. PALMER.
